(57) **CLAIM**

The ornamental design for a lever handle substantially as shown and described.

DESCRIPTION

FIG. 1 is a Front perspective view of the lever handle showing an environment in which the lever handle may be used;

FIG. 2 is a top front perspective view of the lever handle shown in FIG. 1;

FIG. 3 is a bottom back perspective view of the lever handle shown in FIG. 1.

FIG. 4 is a front view of the lever handle shown in FIG. 1;

FIG. 5 is a rear view of the lever handle shown in FIG. 1;

FIG. 6 is a right side view of the lever handle shown in FIG. 1;

FIG. 7 is a left side view of the lever handle shown in FIG. 1;

FIG. 8 is a bottom view of the lever handle shown in FIG. 1; and,

FIG. 9 is a top view of the lever handle shown in FIG. 1. The broken lines showing the door and wall in FIG. 1 are included for the purpose of illustrating environment of the claimed design, while all other broken lines are included for the purpose of illustrating portions of the lever handle; the broken lines form no part of the claimed design.
